UNITED STATES PATENT OFFICE.

CLYDE J. COLEMAN, OF NEW YORK, N. Y.

SCREEN.

1,258,192.

Specification of Letters Patent.

Patented Mar. 5, 1918.

Application filed June 6, 1912. Serial No. 702,075.

To all whom it may concern:

Be it known that I, CLYDE J. COLEMAN, a citizen of the United States, and a resident of New York, county of New York, and State of New York, have invented certain new and useful Improvements in Screens, of which the following is a specification.

My invention relates to screens, and more particularly to screens upon which moving pictures and stereopticon views are projected.

One object of my invention is to provide a screen in which the illumination effect or amount of light is greatly increased, so that the image is rendered more distinct and vivid, and yet at the same time the screen may be cheaply and easily made and is flexible, so that it may be conveniently carried from place to place and easily put up. Further objects, features and advantages will more clearly appear from the detailed description given below taken in connection with the accompanying drawing which forms a part of this specification.

The figure of the drawing illustrates a section of a portion of a screen embodying my invention in one form.

Referring to the drawing, 1 represents the body portion which is made of flexible material, such as a sheet of celluloid. However, any other suitable flexible material may be used.

Applied to one side of the body portion 1 is a silver coating 2 forming a reflecting surface on one side of the body portion. On the same side of the body portion 1, and over and upon the coating 2 is applied a partially opaque coating 3 adapted to transmit some light rays therethrough to be reflected by the silver coating 2. The coating 3 may consist of transparent varnish or lacquer with a small addition of powdered magnesium or other suitable material, so as to form a more or less semi-transparent coating. It is not necessary, however, that the coating be made partially opaque by the inclusion of powdered material as any suitable partially opaque coating may be used. A transparent rubber coating or a coating having a small amount of white coloring matter therein may be used with success.

In operation, an image being thrown upon a screen the light used for defining the image first strikes the face 4 of the coating 3 and is in a great measure reflected and

diffused by this face. The portion of the light which manages to pass this face however, is not wasted. It is transmitted through the coating 3, and striking against the silver coating or reflecting surface 2 is reflected back, and increases the degree of illumination of the surface 4.

I am aware that it has been suggested to use a ground glass with a reflecting back, but my arrangement has distinct advantages over such a screen since my improved screen is flexible, thus enabling it to be more easily put up and carried from place to place, as well as being far less expensive to manufacture, especially when the screens are of considerable size. And furthermore, my improved screen has a further distinct advantage in that the coating 3 is comparatively thin so that the rays of light are reflected at a point very near the surface 4, and thus those rays which pass through the coating 4 at an angle thereto are reflected back substantially to the same point at which they strike the surface 4. In those screens in which the rays of light pass through a plate of glass the glass is of necessity very much thicker than the coating 4 and therefore the rays of light which pass through the glass at an angle to its surface are reflected back to the surface at a point quite some distance from the point at which they enter, thus tending to cause a blurring of the image.

The formation of the coating 3 by using a transparent varnish or other material and placing therein a powder for making it partially opaque forms a simple method for producing the partially opaque coating.

Although I have described my improvements in great detail and with respect to certain particular embodiments thereof, nevertheless I do not desire to be limited to such details since many changes and modifications may well be made without departing from the spirit and scope of my invention in its broader aspects.

Having fully and clearly described my improvements what I claim is new and desire to secure by Letters Patent, is:

1. A screen of the class described, comprising a flexible body portion having a coating on one side adapted to form a reflecting surface on that side and a partially opaque coating over the first coating, both of said coatings being on the same side of the body portion and the first coating being

adapted to reflect light rays transmitted through second coating and said second coating comprising a transparent material with a powder therein for making it partially opaque.

5 2. A screen of the class described, comprising a flexible body portion having a coating on one side adapted to form a reflecting surface on that side and a partially opaque coating over the first coating, both

10 of said coatings being on the same side of the body portion.

In testimony whereof, I have signed my name to this specification, in the presence of two subscribing witnesses.

CLYDE J. COLEMAN.
